REFLECTIVE SIGN STRUCTURE

Gustave M. Reininger, Fort Mitchell, Ky.

Application April 27, 1939, Serial No. 270,365

2 Claims. (Cl. 40—135)

This invention relates to a reflective sign structure or display device having a luminescent characteristic dependent upon extraneous light directed thereon.

5 An object of the invention is to provide a reflective sign or display structure having superior attractiveness and reflective properties, although the structure embodies a simplicity of construction heretofore unknown in devices of its kind.

10 Another object of the invention is to provide a sign or display structure having the improvements mentioned, which may be manufactured inexpensively with a saving of labor and costly materials.

15 A further object of the invention is to provide a reflective sign structure including means for accomplishing a directional luminescence so as to adapt the sign structure to various environments, thereby securing the maximum attractiveness and brilliance under conditions of changing surroundings without bodily moving or re-locating the entire sign structure.

Another object of the invention is to improve upon the manner of assembly of a sign structure, 25 to avoid frequent servicing and rapid deterioration of its reflective properties.

These and other objects are obtained by the means described herein and disclosed in the accompanying drawing, in which:

30 Fig. 1 is a plan view of a reflective sign structure embodying the invention.

Fig. 2 is an enlarged cross-sectional view taken on line 2—2 of Fig. 1.

Fig. 3 is a plan view of a modified form of reflective sign structure embodying the invention.

35 Fig. 4 is an enlarged cross-sectional view taken on line 4—4 of Fig. 3.

Fig. 5 is a view similar to Fig. 4, illustrating a modification thereof.

40 The display or sign structure of the present invention comprises, in accordance with Figs. 1 and 2, a substantially flat plate 7 of glass or other translucent material, having opposed front and rear faces 8 and 9, respectively. The front

45 face 8 is provided with a multiplicity of light-diffusing surfaces preferably in the form of small lenses or hemispherical protuberances 10 which are formed integral with the translucent plate. In the preferred form of the invention, the small

50 protuberances are substantially of uniform size and equal spacing over the entire front face of the plate. The lower left hand corner of Fig. 1 exemplifies the nature of the front face of plate 7, it being understood that in practice the protuberances extend over the entire area 8. While

55 it may be possible to form the protuberances with various shapes or configurations, superior results have been accomplished by making them hemispherical so as to accomplish a lense effect rather than a prismatic effect.

A sign or display character indicated at 12 is applied to the rear face 9 of the translucent plate in any suitable manner, such as by painting or any other process commonly employed in the application of sign letters or display characters upon signs of presently known types. It is of course possible to apply the character 12 by means of painting, transfers, foils, etching, sand blasting and the like. Those portions of the rear face which do not bear the sign or display character, are treated with a coating or sheeting 13 of reflecting material. This may be accomplished with the use of a silvering compound, a foil, or other brilliance reflecting sheet or coating, as may be desired.

15 The foregoing is an explanation of the simplest form of the invention, which has proven attractive due to the lens effect of the multiplicity of protuberances 10, which produce a soft but highly brilliant reflection of extraneous light imposed upon the outer or front face 8 of the sign structure.

In accordance with Figs. 3 and 4, the translucent plate likewise is provided with the multiplicity of small protuberances 10 upon the front 25 face 8 of the sign structure, but in this form of the device, the entire rear face is silvered or otherwise rendered brilliantly reflective by means of a sheet or coating 13 of the character referred to above. The sign or display character of Figs. 30 3 and 4 is distinguished by reason of the fact that it is formed in the nature of apertures such as 14 and 15 provided in a face plate 16 which covers the front face of the translucent body 7. The plate 16 may be of sheet material which 35 which is preferably opaque, so that those protuberances or miniature lenses which do not show through the apertures 14 and 15 are covered by the face plate 16. While it is possible to form the face plate 16 from various kinds of 40 sheet material, it is highly desirable to utilize metal or some material that may be bent along two or three of the edges of the translucent body 7, to provide flanges such as 17 and 18 arranged in channel formation to receive and hold 45 the translucent plate. The areas of the face plate 16 which have not been cut away, overlie a considerable number of the protuberances 10, and may contact them as illustrated in Fig. 4. In forming certain types of letters or display 50 characters, it is considered desirable to provide narrow strips such as 19 between the apertures or cut-outs indicated at 14 and 15, to establish the integrity of the letter or display character.

55 In both of the structures thus far illustrated and described, it is deemed desirable to apply to the back of the sign structure a protective sheet or coating 20, so that the silvered and painted areas will not be readily injured or de- 60

faced during handling or use of the sign structure. The sheet or coating 20 may be of any desired character, it being customary to apply it as a paint having wear resisting qualities.

- 5 In the modification of Fig. 5, the structure will have the outward appearance of the Fig. 3 disclosure, since the plate 16 with its apertures 14 and 15 is employed in combination with a translucent plate 7 as previously explained. In the 10 Fig. 5 modification, however, the rear face 9 of the translucent plate 7 is permitted to remain untreated, so that the plate 7 is translucent throughout, and said plate is backed by a second translucent plate 27 which, by preference, though 15 not of necessity, is identical to the plate 7. The translucent plate 27 has its plain face 26 untreated so that it is clear and transparent, whereas the plate 25 which carries the light-diffusing means 30 is backed or coated with a 20 reflecting coating or sheeting 31. A protective coat or sheet 32 may be applied over the reflecting material 31.

The light-diffusing means of plate 27 should be the same as is indicated at 10, that is, it 25 should be constituted of a multiplicity of hemispherical protuberances or miniature lenses of the same size and spacing as those of plate 7. The reason for this is that plate 27 is rendered shiftable relative to the plate 7 so that light rays penetrating the lenses of plate 7 will impinge upon the reflective lenses of plate 27, and be thrown back through the front face 8 of plate 7 directionally, dependent upon the positions assumed by the lenses 30 with relation to the lenses 10. The plate 27 may be rendered shiftable in any suitable manner, such as by means of a plurality of shims or spacers 33 and 34 provided at opposite ends of the plate. By shifting the shims from one end of the plate to the other, 40 the relationship of the lenses 30 to the lenses 10 may be varied, so that the extraneous light rays emanating from a source at any angle to the front face of the sign structure, may be reflected back directionally under complete control of a sign erector, by manipulation of the groups of 45 shims 33 and 34.

The primary advantage of the Fig. 5 construction, in addition to the advantages resulting from the use of hemispherical protuberances or lenses 50 10 on the front face of the sign, is that the sign may be erected on a building, or upon a roof or elsewhere, and thereafter adjusted as to its brilliancy, taking into consideration the angularity between the observer's point of view and 55 the location of extraneous light source which the sign erector desires to take advantage of for illuminating his installation. Should the extraneous light source utilized ever be removed or changed as to location, the sign of Fig. 5 may be 60 adjusted by shifting the plate 27, so as to take advantage of other available extraneous light sources, thereby to again direct reflected rays to a thoroughfare or some portion thereof from which the sign or display of Fig. 5 is to be observed. The shifting of the reflective lenses of 65 plate 27 is easily accomplished and may be performed as often as selected extraneous light sources may be altered as to location. In some instances, a new and more desirable extraneous 70 light source may appear in the vicinity, in which case it may be desirable to adjust the present sign or display so as to take advantage of the new light source.

In the sign structure of Fig. 5, it is considered desirable to provide resilient flanges 35 and 36 along two or three of the plate edges at the rear of the device, so that the contacting faces of plates 7 and 27 may be likewise kept in firm flatwise abutment in order to exclude dirt, condensation, and any other foreign material that might impair the brilliancy of the sign structure. The resilient members 35 may be integral parts of the face plate 16 if desired, but it should 10 be readily evident that the force of contact between the plates 7 and 27 may be achieved in various other ways. Broadly stated, one of the objectives of the Fig. 5 construction is to furnish means whereby the angle of incidence of light 15 rays reflected by the sign structure may be altered at will, to accommodate the sign to varying additions of extraneous light source.

With respect to the disclosures of Figs. 1 to 4 inclusive, it is to be understood that the protuberances or lenses 10 may be applied to the rear face of the sign, if desired, leaving the front face plain. In such a construction, the sign character and the coatings would be applied to the face that carries the protuberances or lenses. 25

It is to be understood that various modifications and changes may be made in the structural details of the device, within the scope of the appended claims, without departing from the spirit of the invention.

30 What is claimed is:

1. In a reflective sign structure of the character described, the combination of a plate of translucent material having opposed front and rear faces, a series of substantially uniform 35 equally spaced hemispherical protuberances extending from the front face of the plate, a reflector plate including a reflecting material and similar protuberances on the rear face thereof so as to be observable through the front face 40 thereof, and a substantially opaque cover apertured in the form of a display character, adapted to overlie the front face and those protuberances of the translucent plate which are in non-regis- 45 tering position with relation to the cover apparatus, and means for selectively adjusting one of the plates for directional reflection of extraneous light rays impinging thereon through the front of the sign structure.

2. In a reflective sign structure of the character described, the combination of a plate of translucent material having opposed front and rear faces, a series of substantially uniform 50 equally spaced hemispherical protuberances extending from the front face of the plate, a substantially opaque cover apertured in the form of a display character, adapted to overlie the front face of the plate and exposing the uncovered protuberances through the cover aperture, and means for backing the plate comprising a shift- 55 able reflector plate having a smooth face resting along the rear face of the first mentioned plate, and having a silvered opposed face including protuberances like that of the first mentioned plate, said reflector plate being movable to positions of adjustment at which extraneous light rays directed thereon through the first plate will be reflected back at an angle dependent upon the adjustment mentioned.

70 GUSTAVE M. REININGER.

CERTIFICATE OF CORRECTION.

Patent No. 2,231,139.

February 11, 1941.

GUSTAVE M. REININGER.

It is hereby certified that error appears in the printed specification of the above numbered patent requiring correction as follows: Page 2, second column, line 45-46, claim 1, for the word "apparatus" read --apertures--; and that the said Letters Patent should be read with this correction therein that the same may conform to the record of the case in the Patent Office.

Signed and sealed this 18th day of March, A. D. 1941.

(Seal)

Henry Van Arsdale,
Acting Commissioner of Patents.
